(57) **CLAIM**

The ornamental design for a hunting decoy, as shown and described.

DESCRIPTION

FIG. 1 is an isometric view of a front and left side an ornamental design of a hunting decoy in a deployed configuration;

FIG. 2 is a front elevational view of the hunting decoy of FIG. 1;

FIG. 3 is a rear elevational view of the hunting decoy of FIG. 1;

FIG. 4 is a right side elevational view of the hunting decoy of FIG. 1;

FIG. 5 is a left side elevational view of the hunting decoy of FIG. 1;

FIG. 6 is a top plan view of the hunting decoy of FIG. 1;

FIG. 7 is a bottom plan view of the hunting decoy of FIG. 1;

FIG. 8 is an isometric view of a front and right side of the hunting decoy of FIG. 1 in a folded configuration;

FIG. 9 is a front elevational view of the hunting decoy of FIG. 8;

FIG. 10 is a rear elevational view of the hunting decoy of FIG. 8;

FIG. 11 is a left side elevational view of the hunting decoy of FIG. 8;

FIG. 12 is a right side elevational view of the hunting decoy of FIG. 8;

FIG. 13 is a top plan view of the hunting decoy of FIG. 8; and,

FIG. 14 is a bottom plan view of the hunting decoy of FIG. 8.

The broken lines are included for the purpose of illustrating portions of the hunting decoy that form no part of the claimed design.
